LAST.

1,259,140.

Specification of Letters Patent. Patented Mar. 12, 1918.

Application filed April 15, 1914. Serial No. 831,979.

To all whom it may concern:

Be it known that I, JOHN C. SCHELTER, a citizen of the United States, residing at Rochester, in the county of Monroe and 5 State of New York, have invented certain Improvements in Lasts, of which the following description, in connection with the accompanying drawings, is a specification, like reference characters on the drawings indicating like parts in the several figures.

Divided lasts of the more common commercial types usually comprise a fore part, a heel part, and bonding means for connecting said parts in such a manner that the parts 15 are enabled to swing from an extended or straightened relationship into a collapsed or shortened relationship. These lasts are usually always turned in a solid one-piece form and are then so divided as to form the 20 desired abutting faces on the adjacent ends of the fore and heel parts, after which the bonding or connecting means are inserted in the respective parts and secured therein. The fastenings by which the bonding means 25 is secured do not settle firmly into the wood when the last is first assembled and it is usually found that, if the last is assembled in such a manner that it will straighten freely when it is new, there will be enough slack in 30 the connections to cause some looseness or wobble between the fore and heel parts after the last has been used a short time. On the other hand, if the last is assembled tightly enough to allow for this slack, it will be 35 difficult to close or straighten when first put into use. Accordingly, it is the usual practice to treat the lasts before they are completed in some manner designed to take the stretch or slack out of the bonding means 40 and settle the fastenings firmly into the fore and heel parts.

One method of obtaining this result is to assemble the last parts so tightly that they can be straightened only with some difficulty, then to partly collapse the last and to insert between the abutting faces of the fore and heel parts near their bottom surfaces a thin sheet of metal. The last is then supported bottom upward on its toe and heel 50 parts, leaving the middle of the last unsupported, and is struck a heavy blow with a rawhide mallet. This operation, of course, settles the rivets or other means, by which the connections are anchored in the two 55 parts, firmly into the wood and takes out any

slack that might previously have existed in this connection. After the sheet of metal has been removed from between the abutting surfaces it usually will be found that the heel part will swing easily into its proper 60 extended relation to the fore part with the abutting surfaces of the parts meeting smoothly. This procedure, however, results in breaking a substantial proportion of the lasts so treated. It is an important object 65 of this invention to devise a divided last in which the fore and heel parts can be properly adjusted without danger of injuring the lasts.

It is a further object of the invention to 70 devise a bonding means for the fore and heel parts of the last which will enable the last to shorten rapidly at the beginning of its collapsing movement. This is a very desirable feature since it not only avoids any 75 binding of the heel part of the last against the lining of the shoe at the heel in withdrawing the last, but also makes it very much easier to insert the last in the shoe without wrinkling the lining or injuring the 80 counter.

It is also an object of the invention to devise a connection for the fore and heel parts of a last which can be conveniently removed from the fore part if it is desired to discard 85 this part of the last for any reason, as for instance where a standard heel part made of metal or other relatively indestructible material is employed.

These and other objects of the invention 90 will be readily understood from the following description of one embodiment thereof, reference being made to the accompanying drawings, in which,

Figure 1 is a side elevation of a last constructed in accordance with this invention; and

Fig. 2 is an angular view showing the connection between the fore and heel parts, the heel part of the last being shown in vertical 100 cross-section.

The construction shown comprises a fore part 2 and a heel part 4. The fore part has a sharply inclined rear end face 6 that extends downwardly from the top of the last 105 to a point a short distance above its bottom face and the heel part has a backwardly inclined end face 8, these two faces providing an open V-shaped space between the upper portions of the two parts of the lasts. The 110

fore part 2 also has an abutting face 10 lying back of the plane of the face 6 and extending upwardly and forwardly from the bottom of the last at a considerable angle to the 5 bottom face, and this face abuts against a corresponding face on the forward end of the heel part 4. A short horizontal surface 12 is formed on the fore part 2, beginning at the upper edge of the face 10 and extending 10 forwardly; while a corresponding horizontal face on the heel part 4 overlies and rests on the face 12 when the parts are in their extended positions, as shown in full lines in Fig. 1. The face 6 may be continued until it 15 meets the surface 12 or these two surfaces may be connected by a curved face 13 forming a recess in the rear end of the fore part, as shown in Fig. 1.

The heel part is bonded to the fore part 20 by means of a hinge consisting of two bolts or dowels 14 positioned in holes drilled horizontally into the heel part 4 just above the face 12, and a pair of corresponding bolts 16, positioned in holes drilled horizontally in 25 the fore part 2 opposite the holes in the heel part. These bolts are each provided with a head or knuckle that lies just above the face 12 of the fore part and at the bottom of the V-shaped space between the faces 6 and 8 of 30 the fore and heel parts, respectively. A transverse pivot pin 18 extends through these knuckles and hinges the bolts 14 to the bolts 16. The two bolts 14 are secured in the heel part by means of a pin 20 that ex- 35 tends transversely through both the heel part and the end portions of the bolts.

A horizontal hole is bored transversely through the fore part 2 at right angles to and opening into the ends of the holes in 40 which the bolts 16 are positioned. In this hole a sleeve 22 is rotatably mounted and this sleeve has an eccentric bore, as clearly shown in the drawings. Each of the bolts 16 has at its forward end a head 24 that is 45 connected to the bolt by a short reduced neck 25. The eccentric sleeve 22 has two keyhole slots 26 cut in its periphery, the large part of each slot being of sufficient dimensions to receive the head 24 of one of the bolts 16, 50 while the reduced part of the slot is of a width just sufficient to receive the neck 25 by which the head is connected to the bolt. Consequently, when the necks 25 are in the 55 reduced parts of the slots, the heads 24 will bear against the inner surface of the sleeve 22. It will be seen from an inspection of Fig. 2 that the large part of the slot is cut in the thinnest part of the sleeve 22, while the narrow part of the slot extends through 60 the thickest part of the sleeve. Accordingly, when the heads of the bolts are positioned in the sleeve, as they are shown in the drawings, and the sleeve is turned, the bolts will be drawn forward, or allowed to slide backward, depending upon the direction of rota- 65

tion of the sleeve. A transverse slot 28 is formed in one end of the sleeve to receive the end of a key, or screwdriver of suitable dimensions, to facilitate the adjustment of the sleeve; and one or more holes 30 are 70 drilled transversely through the sleeve to receive a screw 32 by which the sleeve may be locked against rotation to hold it in any adjusted position. The sleeve 22 extends through a part of the last which narrows 75 very rapidly from bottom to top, and consequently the upper parts of the ends of the sleeves are cut away or beveled off so that each end face of the sleeve will lie substantially flush with the lateral faces of the last 80 in all positions of its adjustment. The holes 30 are drilled through the sleeve close to its end and opposite the cut away portion in such a manner that when a screw 32 is inserted in one of the holes 30 it may be driven 85 by a screw-driver in the usual way, the shank of the screw-driver being positioned in the cut away portion of the sleeve.

Assuming the fore and heel parts of the last to be completed, they are assembled by 90 assembling the hinge; then inserting the bolts 14 in the heel part; securing them therein by means of the pin 20; inserting the sleeve 22 in the fore part with the large part of the keyhole slots 26 in alignment 95 with the holes in which the bolts 16 are received; and then inserting these bolts in the holes in the fore part until their heads 24 are entered in the respective slots 26 of the sleeve. The sleeve 22 is then turned by 100 means of a key inserted in the slot 28, thus drawing the hinge, and with it the heel part 4, longitudinally of the last until the abutting faces of the heel and fore parts are adjusted in contact with each other with the desired pressure. The screw 32 is then inserted in the hole 30 and forced into the fore part, thus locking the sleeve 22 in its adjusted position. The cam-like action of the 105 sleeve on the heads of the bolts enables a workman to draw the fore and heel parts together as tightly as he desires.

The neck 25 connecting each head 24 with its respective bolt 16 preferably is longer than the maximum thickness of the eccentric sleeve 22. This construction provides for a certain amount of lost motion between the bolts 16 and the sleeve 22 and allows the heel part to slide forward relatively to the fore part as soon as it is swung out of 110 its extended position. This sliding movement also effects a forward movement of the pivot 18 so that the heel part is moved forward with relation to the center about which the initial swinging movement began. 115 The adjacent end faces of the fore and heel parts, of course, are constructed to permit this sliding movement. Accordingly as soon as the heel part 4 begins its collapsing movement, the bolts 16 are allowed to slide for- 120 125 130

ward in the fore part 2, thus permitting the abutting face of the heel part to slide forward on the corner formed by the faces 10 and 12 of the fore part, carrying the back 5 of the heel away from the counter and lining of the shoe in which the last is positioned. Thereafter the collapsing movement of the heel part may be completed without the heel part binding in the shoe, the location 10 of the pivot 18 with relation to the fore and heel parts being such that the continued swinging movement of the heel tends to shorten the last still further. The dotted line position of the heel part in Fig. 1 shows 15 the heel just after it has slid forward as above described. When the last is to be extended, the upper edge of the face 10 may serve as a fulcrum, upon which the corresponding heel part face may slide and rock 20 as the lost motion in the bonding means is taken up and the heel part settles into extended position.

If desired, a lock may be provided to hold the last in its extended position and this lock 25 may be of any convenient construction. In the form shown, it consists of a bracket 32' secured to the face 6 of the fore part and having pivoted thereto a strut 34 adapted to be swung either into engagement with the 30 face 8 of the heel part where it will lock the last in its extended condition, or into an inoperative position parallel to the face 6 where it will permit the last to collapse. A spring 36 tends to hold the strut 34 in its 35 operative or locking position.

In order to guard against the possibility of splitting the last horizontally through the apertures in which the parts 16 and 22 are positioned, the fore part may be reinforced by a wood screw 38 or other suitable 40 means preferably located behind the sleeve 22 and between the bolts 16 and extending in the direction of the height of the last from the last bottom to a point in the in- 45 step portion of the fore part.

The hinge or its adjusting means can not work loose during the use of the last, but the heel part may be disconnected from the fore part at any time by removing the screw 32, 50 rotating the sleeve 22 until the large portions of the keyhole slots come into alignment with the bolts 16, and then withdrawing the bolts and later withdrawing the sleeve. This connection, therefore, is of particular 55 utility in lasts having standard heel parts designed to be used with a number of interchangeable fore parts. Sometimes a last is subjected to such severe strains in the process of manufacturing a shoe, particularly in the leveling operation, that the connections between the fore and heel parts are stretched enough to introduce some looseness between these parts or to disturb their alignment. With the arrangement above de- 60 scribed, this difficulty can be remedied at any

time by removing the locking screw 32 and adjusting the sleeve 22 sufficiently to draw the heel and fore parts together in their proper relationship. The screw 32, of course, should then be replaced to hold the 70 parts in their adjusted positions.

While the embodiment of the invention above described includes features by which all of the objects heretofore mentioned are accomplished, it will be readily understood 75 that these features can be used independently of each other without departing from the spirit or scope of the invention.

Having thus described my invention, what I claim as new and desire to secure by Letters Patent of the United States is:

1. In a divided last, the combination with a heel part and a fore part constructed to have a relative movement into collapsed or extended relationship, of bonding means connecting said heel and fore parts, and means extending transversely of the last and co-operating with said bonding means to effect a relative adjustment of the fore and heel parts longitudinally of the last. 85

2. In a divided last, the combination with a heel part and a fore part constructed to have a relative movement into collapsed or extended relationship, of bonding means connecting said heel and fore parts, and means mounted in the fore part of the last and extending transversely thereof arranged to co-operate with said bonding means to effect a relative adjustment of the fore and heel parts longitudinally of the last. 90

3. In a divided last, the combination with a heel part and a fore part constructed to have a relative movement into collapsed or extended relationship, of bonding means connecting said heel and fore parts, and rotatable means extending transversely of the last and engaging said bonding means in such manner as to effect by its rotative movement a relative adjustment of said fore and heel parts longitudinally of the last. 100

4. In a divided last, the combination with a heel part and a fore part constructed to have a relative movement into collapsed or extended relationship, of bonding means connecting said heel and fore parts, and an eccentric co-operating with said bonding means to effect a relative adjustment of the fore and heel parts longitudinally of the last. 105

5. In a divided last, the combination with a heel part and a fore part constructed to have a relative movement into collapsed or extended relationship, of bonding means connecting said heel part and fore parts, an eccentric rotatably mounted in the fore part 115 of the last in engagement with said bonding means and arranged to effect an adjustment of the bonding means longitudinally of the last, and means for holding said eccentric in an adjusted position. 120

6. In a divided last, the combination with a heel part and a fore part constructed to have a relative movement into collapsed or extended relationship, of bonding means connecting said heel and fore parts, a rotatable device extending transversely of the last and arranged to engage said bonding means in such manner as to effect by its rotative movement a relative adjustment of the fore and heel parts longitudinally of the last, and means for locking said rotatable device against rotative movement to hold it in adjusted position.

7. In a divided last, the combination with a heel part and a fore part constructed to have a relative movement into collapsed or extended relationship, of bonding means connecting said heel and fore parts, an eccentric rotatably mounted in engagement with said bonding means and arranged to coöperate with said means to effect through its rotative movement a relative adjustment of the heel and fore parts toward or from each other, and means for locking said eccentric against rotative movement to hold it in adjusted position.

8. In a divided last, the combination with a heel part and a fore part constructed to have a relative movement into collapsed or extended relationship, of bonding means connecting said heel and fore parts, an eccentric sleeve rotatably mounted in one of said last parts and having engagement with said bonding means enabling it to adjust said means longitudinally of the last, and means for securing said sleeve against rotative movement to hold it in adjusted position.

9. In a divided last, the combination with a heel part, a fore part, and bonding means connecting said parts to enable the heel part to swing relatively to the fore part to collapse or extend the last, of an eccentric device for securing said bonding means to one of said last parts, said device being adjustable to move said means longitudinally of the last, and means for holding said eccentric device in adjusted position.

10. In a divided last, the combination with a heel part, a fore part having a transverse bore, and bonding means connecting said parts to enable the heel part to swing relatively to the fore part to collapse or extend the last, of an eccentric sleeve rotatably mounted in said transverse bore, said sleeve being provided with one or more peripheral slots and said bonding means having parts entering said slots and engaging the inner surface of the sleeve whereby a turning movement of the sleeve operates to move the bonding means longitudinally of the last, and means for securing said sleeve in adjusted position.

11. In a divided last, the combination with a heel part, a fore part, and bonding

means connecting said parts and enabling the heel part to swing relatively to the fore part to collapse the last, of adjusting means coöoperating with said bonding means to effect a relative adjustment of the fore and heel parts longitudinally of the last, said bonding means having a lost motion connection with said adjusting means and said fore and heel parts having their abutting faces shaped to enable said heel part to slide forward during its collapsing movement.

12. In a divided last, the combination with a heel part, a fore part, and bonding means connecting said parts and enabling the heel part to swing relatively to the fore part to collapse or extend the last, of a device mounted transversely in the fore part of the last to secure said bonding means in the fore part, and means positioned between said device and the rear face of the fore part and extending in the direction of the height of the last to reinforce said fore part.

13. In a divided last, the combination with a heel part, a fore part, and bonding means connecting said parts and enabling the heel part to swing relatively to the fore part to collapse or extend the last, of means removably mounted in the fore part of the last for securing said bonding means to the fore part, said means having a connection with said bonding means enabling it to effect a relative adjustment of the fore and heel parts longitudinally of the last and being arranged to release the bonding means from the fore part to permit the removal of the bonding means from the fore part.

14. In a divided last, the combination with a heel part, a fore part, and a hinge connecting said parts and enabling the heel part to swing relatively to the fore part, of an eccentric sleeve removably and rotatably mounted in a transverse bore formed in the fore part, said sleeve having a plurality of keyhole slots formed in its peripheral surface, headed extensions from said hinge arranged to enter said slots and engage the inner surface of the sleeve to secure the hinge to the fore part, and means for securing said sleeve in adjusted position.

15. In a divided last, the combination with a heel part and a fore part having abutting end faces, of bonding means having a single pivot axis connecting said parts and holding said abutting faces in contact with each other when the last is extended but enabling the heel part to swing initially relatively to the fore part to collapse the last, said bonding means and the end faces of said heel and fore parts being constructed and arranged to enable the heel part to slide forward relatively to the center about which the initial swinging collapsing movement of the heel part begins immediately after said initial swinging collapsing movement has begun.

16. In a divided last, the combination with a heel part and a fore part having abutting end faces, of bonding means connecting said parts and holding said abutting faces in contact when the last is extended, said bonding means and said heel parts and fore part being constructed and arranged to enable the heel part to swing initially with relation to the fore part about a center lying between the points of attachment of the bonding means to collapse the last and then to move bodily forward relatively to the center about which the initial swinging collapsing movement of the heel part begins, immediately after said initial swinging collapsing movement has begun. 10
17. In a divided last, the combination with a heel part and a fore part having abutting end faces, of bonding means having means for anchoring it in said last parts, and a pivot distinct from said anchoring means, said bonding means connecting said parts and holding said abutting faces in contact when the last is extended, said bonding means and said heel part and fore part being constructed and arranged to enable the heel part to swing initially with relation to the fore part to collapse the last and, by bodily forward movement of the bonding means, to permit the heel part to move bodily toward the fore part. 20
18. In a divided last, the combination with a heel part and a fore part having abutting end faces, of bonding means connecting said parts and holding said abutting faces in contact when the last is extended, said bonding means and said heel part and fore part being constructed and arranged to enable the heel part to swing initially about a center with relation to the fore part to collapse the last and then by forward movement of that center, to enable the heel part to move bodily toward the fore part immediately after the initial swinging collapsing movement has begun. 30
19. In a divided last, the combination with a heel part and a fore part having abutting end faces, of bonding means connecting said parts and holding said abutting faces in contact when the last is extended, said bonding means and said heel part and fore part being constructed and arranged to enable the heel part, first, to swing initially about a center with relation to the fore part, second, to move bodily forward relatively to the fore part and, third, to swing farther toward the fore part about a center in advance of the first mentioned center. 40
20. In a divided last, the combination with a heel part and a fore part having abutting end faces, of bonding means connecting said parts and holding said abutting faces in contact when the last is extended, said bonding means, heel part and fore part being constructed and arranged to enable the heel part to swing initially with relation to the fore part about a center lying substantially between said last parts to collapse the last, and said bonding means having a lost motion connection with one of said parts whereby the heel part is enabled to move bodily toward the fore part immediately after said initial swinging collapsing movement has begun. 50
21. In a divided last, the combination with a heel part and a fore part having abutting end faces, of bonding means non-rotatably mounted in said last parts connecting said parts and holding said abutting faces in contact when the last is extended, said bonding means, heel part and fore part being constructed and arranged to permit the collapse of the last by an initial swing of said heel part followed by a movement of translation of said heel part relative to said fore part. 60
22. In a divided last, the combination with a heel part and a fore part having abutting end faces, of bonding means rigidly mounted in one of said last parts connecting said parts and holding said abutting faces in contact when the last is extended, said bonding means, heel part and fore part being constructed and arranged to permit the collapse of the last by an initial swinging movement followed by a movement of combined swing and translation of the heel part relative to the fore part. 70
23. In a divided last, the combination with a heel part, a fore part, and tension means connecting said parts and constructed and arranged to enable the heel part and a portion of said tension means to swing relatively to the fore part and another portion of said means to extend the last, said tension means having a lost motion connection, and one of said fore and heel parts having a fulcrum upon which the other of said parts may turn and slide into extended position while taking up the lost motion. 80
